UNITED STATES PATENT OFFICE.

DOUGLASS L. ARNOLD, OF CHICAGO, ILLINOIS, ASSIGNOR TO INTERNATIONAL HARVESTER COMPANY, A CORPORATION OF NEW JERSEY.

SPARK-PLUG.

1,376,500.

Specification of Letters Patent.

Patented May 3, 1921.

Application filed June 25, 1919. Serial No. 306,664.

To all whom it may concern:

Be it known that I, DOUGLASS L. ARNOLD, a citizen of the United States, residing at Chicago, in the county of Cook and State 5 of Illinois, have invented certain new and useful Improvements in Spark-Plugs, of which the following is a full, clear, and exact specification.

This invention relates to spark plugs.

10 An object of the invention is to provide a spark plug which will be gas tight, and which at the same time can be readily assembled and disassembled for inspection and cleaning.

15 Another object is to provide a spark plug which will always have the same spark gap, no matter how carelessly it is assembled.

These and other objects, as will herein-after appear in the specification, consist of 20 a spark plug having an insulator, the upper portion of which is tapered, a nut in alinement with said insulator, shoulders on the nut and insulator forming substantially a continuous surface, a hollow casing having 25 an internal shoulder and a gasket between said shoulder and the shoulders on the nut and insulator.

Reference is now had to the accompanying sheet of drawings in which Figure 1 is a 30 longitudinal section through my spark plug; and Fig. 2 is an enlarged sectional view of that portion of my spark plug, showing the end of the nut inclined at an angle forming a continuous surface with the inclined 35 shoulder of the insulator, as hereinafter described and claimed.

This spark plug has a metallic casing 10 which is threaded in the usual way for screwing into a cylinder head, while a hexagonal portion 11 is provided at the upper 40 end to which a wrench may be applied. This casing has a longitudinal bore which is threaded at the upper end and has a shoulder 12, the purpose of which will be 45 hereinafter explained. Into this casing is adapted to be screwed at its upper end a nut 13 which is internally tapered, narrowing toward the upper end. Into this is fitted a tapered insulator 14 which I prefer 50 to make of mica, having a shoulder 15 which is preferably placed at an angle to the longitudinal axis of the insulator, and which preferably lies in substantially the same surface as the lower end 13^a of the nut 13.

55 The surface of the shoulder 12 in the inte-

rior of the casing is also preferably placed at substantially the same angle as that of the shoulders 13^a and 15. A gasket 16 which is preferably made of metal is placed between these shoulders, and acts as a seal. 60

In the center of the insulator 14 is placed a rod 17 which carries at its lower end a head 18 and a spark terminal 19. The upper end of this rod is threaded and carries the usual nut 20 and thumb nut 21. At the 65 lower edge of casing 10 I have placed a spark pin 22 which I have preferably inserted at an angle. It will be noted that by my arrangement of the shoulders with respect to the gasket 16, that as the nut 13 is 70 screwed into the casing 10, the shoulder formed by the lower edge 13^a of the nut 13 will very firmly and uniformly grip the outer edge of the gasket 16 forming a very tight joint through which gas will not be 75 able to pass. At the same time, the inner edge of this gasket presses against the shoulder 15 of the insulator 14, thereby maintaining the insulator tight in the nut 13. By reaming the inside of the nut 13 80 and by turning the tapered portion of the insulator 14 to the same angle and by forcing the nut down upon the insulator I am able to get a joint between these two which is perfectly gas tight. This careful fitting 85 also insures that the spark terminal 19 will always be perfectly centered and hence the spark gap between the terminals 19 and 22 will always remain substantially constant.

While I have preferably shown and de- 90 scribed a spark plug having an insulator of mica, I wish it to be understood that I am not limited to mica, but that the insulator may be made of any suitable insulating ma- 95 terial.

While I have in the above specification de- 100 scribed but a single embodiment of my invention, it is to be understood that it is capable of many modifications. Changes, therefore, in the construction and arrangement of parts may be made which do not depart from the spirit and scope of my invention as disclosed in the appended claims:

1. A spark plug having an insulator, the 105 upper portion of which is tapered, a nut closely fitting said taper, shoulders on the nut and insulator forming substantially a continuous surface inclined to the longitudinal axis of the plug, a hollow casing 110

having an internal shoulder, and a gasket between said shoulder and the shoulders on the nut and insulator.

2. A spark plug having an insulator, the upper portion of which is tapered, a nut in alignment with said insulator, inclined shoulders on the nut and insulator forming substantially a continuous surface, a hollow casing having an inclined internal shoulder, and a gasket between said shoulder and the shoulders on the nut and insulator.

3. In a spark plug, a casing having an internal tapered shoulder, a gasket engaging said shoulder, an insulator having its upper portion tapered and an inclined shoulder at the lower end of the tapered portion, a nut having a tapered bore adapted to fit the tapered insulator and having an inclined surface forming a continuation

of the inclined surface on the insulator, the inclined portion of the nut and insulator co-operating with the gasket and inclined shoulder on the casing to form a gas-tight joint and to maintain the insulator centrally in the casing.

4. In a spark plug, a casing having an internal tapered shoulder, an insulator disposed centrally in the casing, a nut fitted around said insulator, said insulator and nut having inclined shoulder portions forming a substantially continuous surface, and a gasket fitted between the shoulder on the casing and the inclined shoulder portion of the nut and insulator, whereby a gas-tight joint is made.

In testimony whereof I affix my signature.

DOUGLASS L. ARNOLD.
